UNITED STATES PATENT OFFICE

121,048

DESIGN FOR A KNIFE HOLDER

Horner H. Hopkins, Des Moines, Iowa

Application April 26, 1940, Serial No. 91,963

Term of patent 7 years

to all whom it may concern:

Be it known that I, Horner H. Hopkins, a citizen of the United States, and resident of Des Moines, Polk County, Iowa, have invented a new, original, and ornamental Design for a Knife holder, of which the following is a specification, reference being had to the accompanying drawing, forming a part thereof.

Fig. 1 is a front elevational view of a knife holder, showing my design;

Fig. 2 is a side elevational view; and

Fig. 3 is a top plan view thereof.

I claim:

The ornamental design for a knife holder, substantially as shown.

HORNER H. HOPKINS.
